[57] CLAIM

The ornamental design for a combined rear combination lamp and bezel for side marker lamp for a vehicle, as shown.

DESCRIPTION

FIG. 1 is a perspective view of a combined rear combination lamp and bezel for a side marker lamp for a vehicle showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a cross-sectional view taken along line VIII-VIII of FIG. 2.
